Elias F. Key of Lowell, Mass.

Assign to

The Lowell Manufacturing Company, of the same place.

Letters Patent No. 225 Dated Jan'y 24-1866.

Design for a Carpet or Cover.

It is desired to call the attention of the Patent Office, making haste, to the same.

That whom it may concern:

Be it known that Elias F. Key, of Lowell, in the County of Middlesex and State of Massachusetts, have originated and designed a new pattern for carpets or other fabrics, of which the following is fully clear and exact description, received being had before a technical company of drawers, making part of this specification.

This design consists of a series of blocks arranged so that the prominent parts of them, form a diamond as shown in the drawings.

The colors employed for the different portions of the design, may be varied to suit the taste and wish of the manufacturer.

Claim.

What I claim as my invention and desire to secure by Letters Patent, is the Design or Pattern for Carpets or other fabrics, herein set forth.
